UNITED STATES PATENT OFFICE.

ALEXANDER ZEBROWSKI, OF STAMFORD, CONNECTICUT.

PORTRABLE WATER-HEATER.

1,381,533.

Specification of Letters Patent. Patented June 14, 1921.

Application filed October 2, 1920. Serial No. 414,344.

To all whom it may concern:

Be it known that I, ALEXANDER ZEBROWSKI, a citizen of the Republic of Poland, residing at Stamford, in the county of Fair-
5 field and State of Connecticut, have invented certain new and useful Improvements in Portable Water-Heaters, of which the following is a specification.

My invention relates to heating apparatus
10 and has particular reference to portable devices adapted to be submerged in water or other fluid for the purpose of heating the same; and it consists of the novel features
15 of construction, combinations and relative arrangements of parts which will be herein-
after more particularly set forth and then specifically defined in the appended claims.

An important purpose of my invention is to provide a simple and comparatively in-
20 expensive heater having fluid tight joints, adapting it to be submerged in water or other fluid for raising the temperature of the same by heat generated from the burning of gas supplied to the interior of the
25 heater from the ordinary house gas burners, and, further, it is another important purpose of my device to provide a heater of such construction as will produce maximum heat proportionate to the amount of gas
30 used.

My inventive idea is capable of embodiment in a variety of mechanical structures, one of which is shown in the accompanying drawings, but it is to be understood that the
35 structure illustrated is merely intended to disclose the essential features of my invention in a preferred form and that its scope is as defined in the appended claims.

In the drawings, wherein like characters
40 of reference denote corresponding parts in the different views:

Figure 1 is a central vertical section through my improved heater taken on the line 1—1 of Fig. 4;

45 Fig. 2, a view similar to Fig. 1 taken on the line 2—2 of Fig. 4;

Fig. 3, a view similar to Fig. 1 taken on the line 3—3 of Fig. 4.

Fig. 4, a top plan; and

50 Fig. 5, a horizontal section on the line 5—5 of Fig. 1.

Referring to the drawings in detail, 10 designates a shell or casing in the form of

a hollow annulus which is of somewhat peculiar construction and forms the body portion of my improved heater, being formed from any desired or suitable material, preferably by casting, to provide an outer wall 11 and an inner wall 12, which latter is concentric with respect to said outer wall and is spaced therefrom as best shown in Figs. 3 and 5 of the drawings. At an intermediate point in its height this annulus is provided interiorly, that is, interiorly of the inner wall 12, with a horizontally arranged partition 13, separating the open upper and lower ends of the annulus proper, and this partition is centrally provided with a dome 14, having a central flanged opening 15 providing a means of communication through the partition. The inner wall 12 terminates at its lower end in said partition 13, while the outer wall 11 extends below the partition and is outwardly flared and provided with a down-turned marginal flange 16. At 75 preferably diametrically opposite points said annulus has formed therein a plurality of elongated vertically arranged openings 17, which are closed with respect to the space between the walls 11 and 12, but provide a 80 means of communication or circulation between the interior and exterior of the annulus or housing proper. These openings 17 extend from the upper end of the annulus to a point below the partition 13 and 85 within a short distance of the out-turned portion of the outer wall 11, being closed with respect to the interior of the annulus proper, below the partition 13, by walls 18.

A dish-like base in the form of a casting 90 19, including a flat marginal portion 20, is designed for association with the bottom of the annulus or housing 10, with the portion 20 received within the downturned marginal flange 16 and the said portion 20 and outwardly flared portion of the annulus secured together in any suitable manner, as by means of bolts or screws 21. Preferably a gasket 22 of any suitable heat resisting material is interposed between the portion 20 and the adjacent portion of the annulus to prevent leakage of water into the annulus and the casting 19 when the heater is submerged.

The inwardly sloping side walls of the dish-like casting 19 are extended upwardly 105 from the bottom of the casting as at 23 into

frusto-conical shape, and are then turned and tapered inwardly as at 24, into funnel shape and finally terminate in a T-head 25 disposed somewhat below the bottom of the casting. L-shaped tubes 26 are connected at the ends of their shorter arms with the respective ends of the T-head 25 and their longer arms extend vertically upward past the annulus 10 a suitable distance where they 10 open to the atmosphere and have secured thereto a ring 27, said tubes, for compactness of assembly and for purposes of strengthening the heater, having their longer or vertical arms received in semi-circular 15 recesses cut in the marginal portions of the annulus and in the casting 19, as best shown in Figs. 1, 4 and 5 of the drawings. Legs 28 are secured to the casting 19 in any suitable manner whereby the heater is supported 20 in an upright position.

Fitting over the flange defining the opening 15 in the dome 14 is a tube 29 which extends from the lower end of and communicates with a combustion chamber 30 which 25 latter is in the form of a hollow cylinder and has extending from its upper end a tube 31 terminating substantially in the plane of the upper ends of the tubes 26.

At points preferably midway between 30 adjacent openings 17 the upper wall of the annulus 10 has formed therein suitable openings to receive the lower ends of tubes 32 which extend upwardly parallel to the tubes 26 and tube 31 and like said first tubes open 35 to the atmosphere and terminate in substantially the same plane, the ring 27 being provided with recesses to receive the tubes 32 to maintain them properly spaced and enhance the rigidity of the heater structure as an en- 40 tirety.

The upper ends of the openings 17 are bridged by pieces 33 and between a pair of these diametrically opposite bridge pieces and the ring 27 is arranged a pair of small 45 spacing tubes 34, through which extend tie rods 35 which at their upper ends, are provided with eyes 36 and at their lower ends provided with nuts 37, whereby the ring may be rigidly secured to the annulus or housing. 50 Engaged with the eyes 36 are the ends of a bail or handle 38 provided to facilitate lifting and handling of the heater.

A small tube 39 opens at one end into the casting 19 and at its other end is passed 55 through the marginal portions of said casting and housing, while extending downwardly from the top of the heater and fitting over the end of this tube is a second tube 40 provided with any suitable means whereby it 60 may be attached to a gas jet or other source of gaseous fuel, and also with means designated generally at 41, for mixing such fuel with air to obtain the proper combustion mixture.

65 Resting upon the uppermost edge of the

frusto-conical portion of the casting 19 and upon the side walls of said casting is a perforated plate 42, the central portion of which, where it overlies the portion 24, is of frusto-conical shape and closed at its top, 70 while the portion between the uppermost edge of the portion 23 and the side walls of said casting, in cross section, is of upwardly directed convex shape, both the convexed and frusto-conical portions of said plate being perforated or apertured as at 43. This plate is secured rigidly in place by a pair of screws 44 which are passed down through the convexed portion and threaded into lugs 45 projecting from the inner face 80 of the side walls of the casting. 75

The inner wall 18 of the openings 17 is provided with an aperture 46 whereby the fuel flowing into the casting may be ignited, but when the heater is in operation 85 this aperture is closed by a plug 47.

The construction of my improved heater having been described, its operation is believed to be apparent: When gas is admitted through the tubes 40 and 39 it flows 90 into the bottom of the dish like casting 19 and is deflected upward by the walls of the frusto-conical portion 23, passing through the apertured plate 42 into the space between this plate and the partition 13. At 95 the same time air flowing down through the tubes 26 and upward through the funnel like portion 24 passes through the apertures in the conical portion of the plate and mixes with the fuel to produce a proper combustible mixture. The tubes 29 and 31 together with the combustion chamber 30 assure proper burning of the fuel by acting in the nature of a flue, while the hollow annulus and the tubes 32 provide maximum radiating area for the heat to effect raising of the temperature of the water or other fluid within which the heater may be submerged. 10

I claim:—

1. A heater of the character described comprising an annular housing including inner and outer relatively spaced concentric walls, the space between said walls being closed at one end and open at the other, a casting closing the open end of said housing, a partition across the inner wall of said housing, means for supplying fuel and air to said base, combustion means connected with said partition, and radiating means 11 connected with said housing. 12

2. A heater of the character described comprising a housing, a base, air tubes leading to said base, a combustion chamber and tube communicating with said housing, radiating tubes leading from said housing, means for maintaining said air supply and radiating tubes relatively spaced and rigid, all of said tubes being open at their upper ends and terminating in a common plane 13

above said housing, and means for supplying fuel to said heater.

3. A heater of the character described comprising an annular housing, a base detachably connected with said housing, said base including side walls converged upwardly into frusto-conical shape to provide a baffle for fuel entering the base, said walls

being then converged downwardly into substantially funnel shape and terminating in 10 a head, and tubes connected with said head for supplying air to be mixed with fuel entering the base.

In testimony whereof I hereunto affix my signature.

ALEXANDER ZEBROWSKI.
